UNITED STATES PATENT OFFICE

WILL KEMP HAYTHORNE, OF SAN ANTONIO, TEXAS

DESIGN FOR A COMMERCIAL DISPLAY UNIT

Application filed February 17, 1933. Serial No. 47,240. Term of patent 3½ years.

To all whom it may concern:

Be it known that I, WILL KEMP HAYTHORNE, a citizen of the United States, residing at San Antonio, in the county of Bexar and State of Texas, have invented a new, original, and ornamental Design for a Commercial Display Unit, of which the following is a specification, reference being had to the accompanying drawing, forming a part thereof.

The figure is an elevation of a commercial display unit, showing my new design. The article is of the thickness of heavy cardboard.

I claim:

The ornamental design for a commercial display unit as shown and described.

WILL KEMP HAYTHORNE.
